UNITED STATES PATENT OFFICE.

ARTHUR C. HERTHEL, OF DAYTON, OHIO.

BALANCED CRANK-SHAFT.

1,261,527.

Specification of Letters Patent.

Patented Apr. 2, 1918

Application filed November 26, 1917. Serial No. 203,872.

To all whom it may concern:

Be it known that I, ARTHUR C. HERTHEL, a citizen of the United States, residing at Dayton, in the county of Montgomery and State of Ohio, have invented certain new and useful Improvements in Balanced Crank-Shafts, of which the following is a specification.

This invention relates to balanced crank-shafts and has for its object the making of counter-balances for crank-shafts easily and accurately adjustable. Heretofore in such structures the counter-balancing elements have usually been merely cast or otherwise roughly formed, with the result that discrepancies in weight in a counter-balance produces errors for which compensation must be made by other counter-balances. With the device of this invention the counter-balancing can be made so accurate that no vibration will be caused by discrepancies in the counter-balances themselves and vibration of the shaft can be cured to a nicety by the accuracy with which these counter-balances can be adjusted by the means herein described.

In the accompanying drawings forming part of this specification, in which like numbers of reference denote like parts wherever they occur,

Figure 1 is a side elevation in which the counter-balance weights are shown upside down as compared to Figs. 2, 3, 4, and 5;

Fig. 2 is a sectional view on the line 2—2 in Fig. 1, looking in the direction of the arrows, but on an enlarged scale;

Fig. 3 is an enlarged side elevation of a crank arm and counter-balance;

Fig. 4 is a section on an enlarged scale on the line 4—4 in Fig. 1;

Fig. 5 is a view taken at a right angle to Fig. 4;

Fig. 6 is a perspective view of a box for Babbitt metal as a means of attachment or bearing for the adjustment bolts;

Fig. 7 is a perspective view of one of the nuts for making adjustment of the counter-balancing weights;

Fig. 8 is a sectional detail through such nut and a bolt passing therethrough, and a cotter pin for holding the same in adjusted position; and

Fig. 9 is a section on a reduced scale on the line 9—9 in Fig. 2.

55 The main shaft 1 of the crank shaft communicates power through the clutch 2 to the

drive shaft 3 connected with the transmission. The timing gear 4 is mounted on the main shaft 1.

The corners of the crank arms 5 are customarily made slanting, as at 6, to overcome which when this invention is used, a box 7 for Babbitt metal is used to square such corners, as clearly shown in Fig. 1, so as to afford a flat bearing surface for the heads 8 of bolts 9, of which there are four for the attachment of each counter-balancing weight 10, as indicated by the bolt holes 11 in the rear wall of box 7.

Counter-sinks 12 in weight 10 receive the ends of bolts 9 and also the nuts 13 which are at the opposite ends of bolts 9 from the heads 8. The belt heads 8 bear against the rear wall of box 7, or in the construction shown in Figs. 4 and 5 for attachment of the counter-balancing weight 14 to the collar 15 on the connecting rod bearings 16, the said bolt heads 8 bear against the plates 17, which are attached by Babbitt metal 18 to collar 15.

50 In the attachment of weights 10 to crank arms 5, the boxes 7 are put on while the Babbitt metal is soft, and the bolts 9 run through the holes 11 in such box and through the passages 19 in crank-arm 5 and through 85 the passages 20 in weight 10 to the countersinks 12, where the ends of bolts 9 receive the nuts 13.

The nuts 21 draw bolts 9 into tight relation to crank arm 5, and a cotter pin 22 that 90 passes through one of the holes 23 in nut 21 and also through a transverse hole through bolt 9 (as best seen in Fig. 8) tightly holds bolts 9 in fixed relation when once set. A duplicate nut 21 and cotter pin 22 acts as a 95 lock nut for the nuts 21 nearest to arm 5. Although the ends of bolts 9 adjacent to nuts 13 and as far as their point of emergence from arm 5 are threaded, the passages 20 are not threaded, and after the nuts 21 100 have been screwed to the position shown in Fig. 2, the weight 10 can slide freely upon bolts 9. Nuts 24 and lock-nuts 25 are each provided with a cotter pin like the cotter pins 22, which cotter pins pass through the 105 holes 23 in nuts 24 and 25, and drill through bolt 9 opposite the same.

After bolts 9 have been secured in arm 5 by nuts 21, as hereinbefore described, the threaded ends of bolts 9 are pushed through 110 passages 28 so as slightly to enter into slots 27, in which nuts 24 and 25 have been placed

so as to thread upon bolts 9 as the said bolts enter the said slots. Rotation of the nuts 24 and 25 threads the said nuts farther on the bolts 9, gradually drawing weight 10 along 5 bolts 9, and nuts 24 and 25 occupy the position depicted in Fig. 2. In the drawings, slots 27 are necessarily exaggerated in size, but in fact nuts 24 and 25 will fit very closely therein.

10 The adjusting is done with nuts 24 and 25 which move in either direction upon the threaded part of bolts 9. By this construction the weight 10 may be drawn nearer to the crank arm 5 or pushed farther out, the 15 pull and push being exercised by the threads within nuts 24 and 25 and on bolts 9. A cured adjustment to the precise degree desired will be made by nuts 24 and 25 whereupon the same will be fixed by cotter pins 20 and locked by nuts 25 through which cotter pins 22 also pass, the said cotter pins extending from one side of nuts 24 and 25 through bolts 9 and out at the opposite side of the said nuts. The adjustment of the 25 nuts 24 and 25 will be made by a spanner wrench in a well understood manner, which will permit of the nuts 24 and 25 being drawn so tightly as to produce precisely the adjustment desired. The nuts 13 are 30 screwed home with a socket wrench to the position shown in Fig. 2, and serve as lock nuts.

Usually on the connecting rod bearings 16 a collar 15 having more or less rough surface is found, which makes necessary the use of Babbitt metal 18 and the relatively smooth plate 17 to afford even bearing for the bolt heads 8, and this construction is duplicated at the opposite side of the said 40 collar 15 for the bearing of nuts 21. The bolts 9 pass through the main shaft 1 in the attachment of the weight 10 to crank arms 5 and other bolts 9 pass through the connecting rod bearing 16 in the attachment 45 to collar 15 of the weight 14.

The weight 10 or the weight 14 need not be of the shape shown in the drawings, but may be of any suitable form. It need not be attached to the particular crank arm or 50 other part shown in the drawings, but if desired may be elsewhere located. It may be divided into parts and in that way distributed, as may be desired. These weights will be so arranged that one-half of their 55 aggregate will be on one side and the other half on the other side of the axis of rotation of the main crank-shaft 1.

The Babbitt metal is poured into box 7 through hole 26 after cap or box 7 has been 60 suitably placed *in situ* upon bolts 9.

Screw studs that only slightly enter the crank-shaft may be substituted for the bolts 9 at all points where such bolts 9 are shown in the drawings, and, if desired, the boxes 65 7 and Babbitt metal may, also, be omitted.

Having thus described this invention, I hereby reserve the benefit of all changes in form, arrangement, order, or use of parts, as it is evident that many minor changes may be made therein without departing 70 from the spirit of this invention, or the scope of the following claims.

I claim:

1. In a balanced crank shaft, the combination of a weight having passages there- 75 through, bolts fixed in their relation to the crank shaft and passing through the passages in the said weight, stationary nuts on the said bolts and adjusting nuts thereon.

2. In a balanced crank-shaft, the combination of bolts having a fixed relation relative to the said crank shaft and extending outwardly therefrom, a weight mounted relative to the said bolts, nuts for limiting the travel of the said weight relative to the 85 said bolts, and other nuts in connection with the said bolts for adjusting the said weights inward or outward relative to the axis of rotation of the crank-shaft.

3. In a balanced crank-shaft, the combination of bolts having a fixed relation relative to the said crank-shaft and extending outwardly therefrom, a weight mounted relative to the said bolts, nuts for limiting the travel of the said weight relative to the 95 said bolts, and other nuts in connection with the said bolts for adjusting the said weights inward or outward relative to the axis of rotation of the crank-shaft, there being unthreaded passages 100 through the said weight for the passage of the said bolts.

4. In a balanced crank-shaft, the combination of bolts having a fixed relation relative to the said crank-shaft and extending outwardly therefrom, a weight mounted relative to the said bolts, nuts for limiting the travel of the said weight relative to the 105 said bolts, and other nuts in connection with the said bolts for adjusting the said weights 110 inward or outward relative to the axis of rotation of the crank-shaft, there being unthreaded passages through the said weight for the passage of the said bolts and a countersink in the said weights adjacent 115 the e. d. of each of the said bolts to receive the said nuts adapted to act as a stop.

5. In a balanced crank-shaft, the combination of bolts having a fixed relation relative to the said crank-shaft and extending 120 outwardly therefrom, a weight mounted relative to the said bolts, nuts for limiting the travel of the said weight relative to the said bolts, and other nuts in connection with the said bolts for adjusting the said weights 125 inward or outward relative to the axis of rotation of the crank-shaft, there being unthreaded passages through the said weight for the passage of the said bolts, there being a cap on an appropriate part of the said 130

crank-shaft to afford even bearing for the heads of the said bolts.

6. In a balanced crank-shaft, the combination of bolts having a fixed relation relative to the said crank-shaft and extending outwardly therefrom, a weight mounted relative to the said bolts, nuts for limiting the travel of the said weight relative to the said bolts, and other nuts in connection with the 10 said bolts for adjusting the said weights inward or outward relative to the axis of rotation of the crank-shaft, there being unthreaded passages through the said weight for the passage of the said bolts, there being 15 a cap on an appropriate part of the said crank-shaft to afford even bearing for the heads of the said bolts, and Babbitt metal for its attachment to the crank-shaft.

7. In a balanced crank-shaft, the combination of bolts having a fixed relation relative to the said crank-shaft and the said bolts, nuts for limiting the travel of the said weight relative to the said bolts, and other nuts in connection with the said bolts for 25 adjusting the said weights inward or outward relative to the axis of rotation of the crank-shaft, there being unthreaded passages through the said weight for the passage of the said bolts, there being a cap on 30 an appropriate part of said crank-shaft to afford even bearing for the heads of the said bolts, and Babbitt metal for its attachment to the crank-shaft, the said cap being shaped like a box.

8. In a balanced crank-shaft, the combination of bolts having a fixed relation relative to the said crank-shaft and extending outwardly therefrom, a weight mounted relative to the said bolts, nuts for limiting the 40 travel of the said weight relative to the said bolts, and other nuts in connection with the said bolts for adjusting the said weights inward or outward relative to the axis of rotation of the crank-shaft, there being unthreaded passages through the said weight for the passage of the said bolts, the said 45 bolts passing through passages leading through longitudinal as well as lateral parts of the crank-shaft.

9. In a balanced crank-shaft, the combi-

nation of bolts having a fixed relation relative to the said crank-shaft and extending outwardly therefrom, a weight mounted relative to the said bolts, nuts for limiting the travel of the said weight relative to the said 55 bolts, and other nuts in connection with the said bolts for adjusting the said weights inward or outward relative to the axis of rotation of the crank-shaft, there being unthreaded passages through the said weight 60 for the passage of the said bolts, the said bolts passing through passages leading through longitudinal as well as lateral parts of the crank-shaft, and being tied thereto by nuts. 65

10. In a balanced crank-shaft, the combination of bolts having a fixed relation relative to the said crank-shaft and extending outwardly therefrom, a weight mounted relative to the said bolts, nuts for limiting the 70 travel of the said weight relative to the said bolts, and other nuts in connection with the said bolts for adjusting the said weights inward or outward relative to the axis of rotation of the crank-shaft, there being unthreaded passages through the said weight 75 for the passage of the said bolts, the said bolts passing through passages leading through longitudinal as well as lateral parts of the crank-shaft, and being tied thereto by 80 nuts, the said nuts being provided with bores and the said bolts being provided with bores adapted to register with the said bores through the nuts and cotter pins adapted for insertion through such registering bores. 85

11. A counter-balance for a crank-shaft comprising a plurality of bolts passing through a part of the said crank-shaft, nuts for fastening the same to the said crank-shaft in tight relation, a weight adapted 90 to be adjusted upon outward extensions of the bolts, stops upon the extremities of the said bolts to hold the said weight upon the said bolts and adjusting nuts adapted to move the said weight toward or from the 95 axis of rotation of the crank-shaft.

In testimony whereof I hereunto affix my signature.

ARTHUR C. HERTEL.
